C. G. DURETT

PORTABLE LOUD SPEAKER

Filed Sept. 14, 1925

FIG. 1.

FIG. 2.

FIG. 3.

Inventor

C. G. Durett,

By A. Patterson, Jr.

Attorneys

Patented June 29, 1926.

1,590,814

UNITED STATES PATENT OFFICE.

CORAL G. DURETT, OF PITTSFIELD, MASSACHUSETTS.

POR TABLE LOUD SPEAKER.

Application filed September 14, 1925. Serial No. 56,211.

The primary object of the invention is the provision of a loud speaker having a collapsible horn whereby the device can be readily and easily carried in one's pocket 5 or can be stowed in a very small space.

Another object of the invention is the provision of a loud speaker which has a collapsible horn which renders the device very small in its collapsed form and is therefore particularly adapted for use with portable radio receiving sets where the conservation of space is quite important.

Another and further object of the invention is the provision of a portable loud speaker which is a complete unit ready for plugging in or connection with a radio receiving set and is so constructed that it can be carried in one's pocket or be stowed in a very small space.

Other objects, novel features of construction and improved results of the invention will appear from the following description and accompanying drawings.

In the drawings:

Figure 1 is a view in side elevation of the invention.

Figure 2 is a vertical sectional view through the horn and a portion of the receiver.

Figure 3 is a side view showing the device in its collapsed form.

Referring to the drawings, in which like parts are designated by similar reference numerals throughout the description, 5 represents an ordinary receiver which is well known in the art. The receiver is provided with an ear piece 6 and the common lead-in wires 7 and 8.

Mounted upon the receiver is a horn A which is held in position by a clamp, the arms 9 and 10 of which engage the receiver 5 as at 11 and 12. The upper ends of the clamp arms 9 and 10 are fastened to the lower horn section or ring 13 which section is in reality a cup, the bottom of which has a circular opening. The peripheral edge 14 of the bottom opening of the horn section 13 is in engagement with the ear piece 6 of the receiver.

In addition to the lower section 13 the horn A consists of the telescoping sections 15 and 16, 17, 18 and 19. As clearly appears in Figures 1 and 2 of the drawings the horn sections are greater in diameter at their outer ends than at their inner ends whereby the sections, when extended, will be held in

extended position through frictional engagement.

The clamp arm 9 extends downwardly beyond the point 11, where it clamps the receiver 5, and inwardly beneath the receiver terminating in a downwardly extending end 20 to which is pivotally fastened as at 21 a plug 22 the inner terminals 23 and 24 of which are connected to the lead-in wires 7 and 8 of the receiver.

By reason of the construction heretofore described the device is collapsible which permits of its storage in a very limited space or it can be readily carried in one's pocket. 70 By reference to Figure 3 it will be seen that the horn sections 15 to 19 inclusive will telescope downwardly and nest upon the receiver while the plug 22 can be swung upwardly upon its pivotal support 21 so as to 75 lie transverse the bottom of the receiver.

Intermediate the end 20 of the clamp arm 9 and the portion 11 which clamps the receiver this arm is bent upwardly as at 25 so as to engage the bottom of the receiver 80 and more firmly and rigidly hold the horn in place.

The horn is preferably made of metal but should it be desirable the horn could be made of fibre, celluloid, paper or any 85 other suitable material. Good results have also been obtained by the use of a metal horn lined with paper.

It will be seen that the portable loud speaker can be marketed and sold as a commercial unit ready for plugging into a radio receiving set.

No special form of receiver is required as the invention can be readily adapted for use with any common well known form of 95 receiver now on the market.

The utility of the invention is very apparent. By reason of the small size of the device in its collapsed form it is very handy to carry about and is especially valuable 100 in portable receiving sets where the conservation of space is important. The invention can however be used with a set which is not portable. In this application the receiver could be mounted in the panel 105 of the receiving set and the horn, when the set is in use, could extend outwardly from the panel. It would not however be necessary to mount the device in the panel of the set as it could be positioned in any convenient place as desired.

By reason of the many uses to which the

invention could be put with other slight changes, attention is directed to the fact that these slight changes would not depart from the spirit of the invention.

5 Having thus described my invention what I claim and desire to secure by Letters Patent is:—

1. A loud speaker comprising a receiver, a clamp having engagement with the receiver, a collapsible horn mounted upon one end of said clamp, and a plug pivotally supported upon the other end of the clamp.

10 2. A portable loud speaker comprising a receiver, a clamp having engagement with the receiver, a telescopic horn mounted upon the clamp in front of said receiver, and a plug pivotally supported upon the clamp.

15 3. A portable loud speaker comprising a receiver having an ear piece, a clamp mounted upon the receiver, a telescopic horn mounted upon the one end of the clamp and having engagement with the receiver

ear piece, and a plug movably mounted upon the other end of the clamp, whereby the horn can be collapsed upon the receiver and the plug swung parallel with the receiver back when the device is not in use.

20 4. A portable loud speaker comprising a receiver, a spring clamp having engagement with said receiver and having one end parallel with the front face of the receiver and its opposite end in engagement with the back of said receiver and outwardly therefrom, a collapsible horn mounted upon the portion of the clamp paralleling the receiver front, and a plug pivotally supported upon the opposite end of the clamp, whereby said plug can be swung to a position parallel with the receiver back when the device is not in use.

25 35 40 In testimony whereof I hereunto affix my signature.

CORAL G. DURETT.
